UNITED STATES PATENT OFFICE.

GLENN W. THURSTON, OF DUNSMUIR, CALIFORNIA.

AUTOMATIC OILING DEVICE.

SPECIFICATION forming part of Letters Patent No. 739,745, dated September 22, 1903.

Application filed March 23, 1903. Serial No. 149,191. (No model.)

To all whom it may concern:

Be it known that I, GLENN W. THURSTON, a citizen of the United States, residing at Dunsmuir, in the county of Siskiyou, State of California, have invented new and useful Improvements in Automatic Oiling Devices, of which the following is a specification.

My invention relates, primarily, to oiling devices for oiling the piston of an air-compressor, and is an improvement on the patent issued to me November 25, 1902, No. 714,337; and the object thereof is to provide an efficient and economical device which will furnish the amount of oil to properly lubricate the piston as it is needed and only when the compressor is running. I accomplish this object by the device described herein and illustrated in the accompanying drawings, in which—

20 Figure 1 is a side elevation of an air pump or compressor used in the air-brake system on railroad-trains with my automatic oiling device applied thereto. Fig. 2 is a central section of so much of my oiling device as 25 illustrates my present improvement.

In the drawings, A is the oil cup or reservoir, having port B in the bottom thereof.

C is the ordinary regulating-screw, by means of which the flow of oil D through port B is controlled. This screw may be provided with a central air-duct C', extending longitudinally therethrough and about one-sixteenth of an inch in diameter. (Shown in dotted lines.) This duct may be omitted; but I prefer to use it. Surrounding port B is a boss A', which is exteriorly threaded and screws into the enlarged top E' of the tube E upon plate a to hold said plate firmly on its seat in said tube. This plate has a boss through which and through the plate is a port B', which is a continuation of port B. In the lower portion of tube E is the downwardly-opening check-valve F, which permits the oil to pass down in the tube whenever a vacuum or partial vacuum is produced in the upper part of the air-compressor b. It is held normally closed or seated by spring G. The opening through tube E is constricted at and just above the check-valve. The lower portion of this constricted portion forms a valve-seat H for the check-valve, and the upper portion thereof forms a support for the

glass sight-tube I, whose lower end has grooves I' extending therethrough, so that air may pass under the sight-tube as well as 55 over the top thereof, as I have found by experience that if all the air comes over the top of the sight-tube the oil is sometimes blown into a spray instead of dropping, as it is better for it to do, so that the engineer may be 60 able to see just how fast the oil is being fed into the compressor. The external diameter of this tube is about one-sixteenth of an inch less than the internal diameter of tube E. Resting upon the top of the check-valve is 65 feed-needle J, having a cylindrical stem J' at the top adapted to close port B when the check-valve F is seated, so that no oil will flow out of the reservoir except when the compressor is running. 70

At the base of stem J' is a circular groove K, having an opening L in the bottom thereof. In this opening I drop a small wire M, which guides the oil passing through the opening and causes it to drop in smaller drops 75 than if it were not used. It may be omitted, if desired; but I prefer its use, because I prefer to have the oil dropped in small drops. The lower portion J'' of the feed-needle is also cylindrical. In this portion of the needle is a groove N, which permits the oil to pass down to the check-valve. A recess O is provided in the side for the reception of the end of screw P, which prevents the feed-needle from rotating, thereby enabling the end 80 of wire M to be seen through sight-port R in tube E. This screw could be placed so that the end thereof would enter groove N and the recess omitted. By this improvement should the compressor stand idle the oil is 85 automatically shut off from the reservoir until it is started up again, thereby economizing the use of oil. If desired, the feed-needle could be made integral with the check-valve, thereby forming a stem on the top or upper 90 end of the check-valve which would close the port when the compressor was not running.

Having described my invention, what I claim as new, and desire to secure by Letters Patent, is—

In an automatic oiling device for lubricating the piston of an air-compressor the combination of an oil-reservoir having a port in the bottom thereof; a tube connected to said

reservoir and communicating with the compressor, said tube having a constricted portion, the under surface of said constricted portion forming a valve-seat, and an opening above said constricted portion adapted to form a sight-port; a glass tube having grooves in the lower end thereof and arranged loosely in said tube above the constricted portion; an upwardly-closing check-valve in said tube below said constricted portion; and a feed-

needle in said tube adapted to close the port in the reservoir when the check-valve is closed.

In witness that I claim the foregoing I have hereunto subscribed my name this 14th day 15 of March, 1903.

GLENN W. THURSTON.
